UNITED STATES PATENT OFFICE.

JAMES E. LADD, OF BRISTOL, CONNECTICUT.

TRUNK-CATCH.

SPECIFICATION forming part of Letters Patent No. 325,347, dated September 1, 1885.

Application filed March 30, 1885. (No model.)

To all whom it may concern:

Be it known that I, JAMES E. LADD, a citizen of the United States, residing at Bristol, in the county of Hartford and State of Connecticut, have invented certain new and useful Improvements in Trunk-Catches, of which the following is a specification, reference being had to the accompanying sheet of drawings.

10 My invention relates to an improvement in so-called "trunk-catches" or "trunk-fasteners," my immediate object being to provide at a moderate cost a catch which combines great strength with extreme simplicity, and 15 which when once locked cannot by reason of accident become loosened and opened.

In the annexed drawings, Figure 1 is a plan view of my improved trunk-catch as it appears when in position on the trunk and is 20 closed. Fig. 2 is a similar view showing the parts as in the act of separation. Fig. 3 is a detached perspective view of the upper or tenon section; and Fig. 4 is a sectional view on line $\alpha\alpha$ of Fig. 1, showing also in dotted lines the tenon b opened, as if about to be 25 withdrawn from its mortise.

The letter A represents the upper half of the base-plate of my device, having secured to the side which engages the companion plate 30 a tenon, b , which extends well downward, and is hinged or jointed at a point near its middle portion. The lower half of the base-plate is represented by the letter B. Said section B is mortised from the side which confronts the 35 tenon b , and is also provided, preferably, with side walls, which extend downward from said mortised portion, thus forming guides to direct the tenon as it is entered in the mortise, and also stiffening to a certain extent the plate 40 B. That portion of the tenon b which extends through the mortise is preferably reduced somewhat in thickness, and, as above stated, is jointed at a point near the center of the reduced portion, so that its outer portion may be folded back upon itself, as shown in Figs. 45 1 and 4, in which position it will be seen that the end of the part thus folded, which is farthest from the joint or hinge, abuts against the inner wall of the mortised portion; and it 50 will be understood that the two parts cannot be again separated until the engaging end of the jointed tenon shall have been disengaged

from the inner wall of the mortised portion. This I do by turning the outer portion of the tenon back into the position shown in Figs. 2 55 and 3.

As a convenient means for retaining the tenon in either an open or a closed position, as desired, I have arranged in a groove in the rear side of said tenon a spring, c , which acts 60 on the flattened inner end of the jointed section substantially as the back spring of a knife acts on a blade. I have also cut under the free end of said jointed section and that portion of the mortise-wall which it engages 65 when closed, for greater convenience in picking up the end of the jointed section.

On the lower end of plate B is a rib, e , cast integral with said plate, on which the tenon rests when opened, the object of said rib being 70 to hold the tenon from close engagement with the plate B, so that said tenon may be easily picked up when it is desired to close the tenon to lock the parts together.

While I have for convenience of description 75 referred to the tenon b as a hinged or jointed tenon, it should be observed that the portion of the tenon which, when the parts are brought together, rests within the mortise is of itself a rigid tenon, and in connection with the mortise-plate forms a dowel, while the outer or hinged portion of b constitutes a locking latch or device, which is hinged to the lower end of said rigid tenon, and is adapted to fasten the parts together by having that end which is 80 farthest from its joint engage a stationary part of the mortise-plate--viz., one of the walls of the mortise.

It should be also noticed that the joint, hinge, or pivot, whichever it may be called, 90 of the tenon, by being located at the outer end of the rigid tenon, must necessarily pass through the mortise, and that it lies in such a position when the parts A and B are fastened together that all strain in a direction to separate 95 said parts is exerted in a direction substantially lengthwise with the locking-latch or hinged portion, whereby I produce a trunk-catch having great strength.

I am aware that a prior patent shows a 100 trunk-fastener containing the dowel system, and having a hooked latch pivoted or hinged to the same plate that bears the dowel-pin or rigid tenon at a point above the tenon proper,

so that only a portion of the locking-latch (and its hinge never) passes into the mortise in the mortise-plate, and I hereby disclaim the same.

5 In practice two of my trunk-catches are generally used—one on each side of the lock proper.

I claim as my invention—

1. In a trunk-catch, a base-plate provided 10 with a mortise, in combination with a companion plate having a jointed tenon adapted to be passed through said mortise and folded backward upon itself, substantially as herein described, and for the purpose specified.

15 2. In combination with a base-plate provided with both the stop-rib *e* and a mortise having extended side walls, a companion plate having a jointed tenon adapted to be passed through said mortise and folded back 20 upon itself to prevent the withdrawal of said tenon, as described, and for the purpose specified.

3. In combination with a base-plate pro-

vided with a mortise and a companion plate having a jointed tenon adapted to be passed 25 through said mortise and then folded backward upon itself to prevent the withdrawal of said tenon, a spring which, bearing on the flattened hinged end of the folding section, acts to hold said section in either an opened or 30 closed position, as desired, substantially as described.

4. In a trunk-catch, a base-plate provided with a mortise, in combination with a companion plate having a rigid tenon adapted to 35 enter said mortise, the two forming a dowel, and a locking device hinged or jointed thereto, said locking device and its joint being located on that part of the tenon which enters said mortise, substantially as described, and 40 for the purpose specified.

JAMES E. LADD.
